UNITED STATES PATENT OFFICE.

GEORGE N. BUCK, OF MATTOON, ILLINOIS.

CLASP.

SPECIFICATION forming part of Letters Patent No. 515,950, dated March 6, 1894.

Application filed February 1, 1893. Serial No. 460,583. (No model.)

To all whom it may concern:

Be it known that I, GEORGE N. BUCK, a citizen of the United States of America, residing at Mattoon, in the county of Coles and State 5 of Illinois, have invented certain new and useful Improvements in Clasps, of which the following is a specification.

My invention relates to a certain new and improved clasp designed for use upon gloves, 10 shoes, or other articles of a similar nature.

The invention is particularly adapted to the class of gloves and shoes in which a loose flap upon one of the meeting edges is stretched over the adjacent edge and fastened down 15 upon it.

The invention is illustrated in the drawings by means of seven figures, of which—

Figure 1 shows the clasp applied to the wrist of a glove, a part of the upper portion only of 20 which is shown. Figs. 2 and 3 are perspectives of the two portions, of which one member of the clasp is preferably made. Fig. 4 is a perspective of the same portions put together. Fig. 5 is a perspective showing the 25 method of applying the said member to the glove or shoe. Fig. 6 is a section in line 6—6, of Fig. 7, showing the same member after its 30 said application, and also the other member in engagement therewith; and Fig. 7 is a section in line 7—7, of Fig. 6.

Looking at Figs. 1, 6 and 7, wherein A is applied to the under loose edge of the wrist of a glove, and B to the loose flap that is stretched over the same, the clasp is seen to be composed of two members, C, D, of which the member, C, is composed of a substantially 35 flat portion, c, secured to the wrist of the glove and having its opposite edges, c', c², turned upward and inward and approaching each 40 other toward the loose edge of the wrist. The member, D, consists of a substantially flat portion, d, joined by a narrow neck, d', to another flat portion, d², fastened to the under side to the loose flap, B. The neck, d', is sufficiently narrow to pass readily between the 45 edges, c', c², and the portion, d, is fitted to slide beneath the up and inturned edges, c', c², but not between them. In engaging the fastening, the member, D, is drawn over upon 50 the member, C, until the flat portion, d, slips

down between the edges, c', c², when it is allowed to slide backward beneath said edges. In this position it is held securely against disengagement in any direction, except by drawing it back the way it went in. The member, 55 C, is preferably composed of two portions, c³, c⁴, shown in Figs. 2 and 3, which said portions contain notches or slots, c⁵, c⁶, entering from opposite ends and the added lengths of the two slits being substantially that of the 60 member, C. In applying this member, C, to the wrist of the glove, a slit, a, is cut in the latter as shown in Fig. 5, the two portions, c³, c⁴, of the member, C, put together as seen in Fig. 4, and their straight edges crowded 65 through the slit, a, as seen in Fig. 5. This slit extends only through the outer thickness of the glove or shoe, and after the member, C, is applied as seen in Fig. 5, the edges, c', c², are spread apart, and the member, C, forced 70 into the position seen in Fig. 6, where the lining, a', of the glove protects the wrist against the edges of the pieces, c³, c⁴.

I claim as new and desire to secure by Letters Patent—

1. A clasp member consisting of two plates each having slots extending from one margin partly across the plate and the two being connected with the two slots in line and with the uncut portion of each plate lying in the 80 slots of the opposite plate, substantially as set forth.

2. A clasp composed of two members, C, D, the member C being bent back upon itself along two opposite sides, forming a channel 85 between the in-turned portions, and consisting of two plates notched to be fitted together and attached to a garment substantially as set forth, and the member D having a tapering portion adapted to wedge between the in-turned parts of the other member, and a portion, to be secured to a garment, connected to said tapering portion by a neck of a width less than the least distance between the in-turned parts of the other member.

GEO. N. BUCK.
